UNITED STATES PATENT OFFICE.

LEWIS J. KNIEL, OF DETROIT, MICHIGAN.

LOCKING DEVICE FOR INTERNAL-COMBUSTION ENGINES.

1,108,995.

Specification of Letters Patent.

Patented Sept. 1, 1914.

Application filed January 28, 1914. Serial No. 815,085.

To all whom it may concern:

Be it known that I, LEWIS J. KNIEL, a citizen of the United States, residing at 143 Henry street, Detroit, in the county of Wayne and State of Michigan, have invented certain new and useful Improvements in Locking Devices for Internal-Combustion Engines, of which the following is a specification.

10 This invention relates to hand-operated locking devices for internal combustion engines, and is particularly designed to provide a simple and effective device for readily disengaging certain operating parts of a gas-engine, and locking them in an inoperative position by a hand-operated means, which locking means can be manipulated to restore the engine parts to operative position, only by a person who knows the combination of the locking elements used.

15 Numerous thefts of automobiles, motorcycles, motorboats, etc., where the thieves have driven the vehicles away under the power of the vehicles' engines demonstrate the great need of a locking device to prevent the operation of such engines by unauthorized persons, while with stationary engines there is also great need of such a locking device to prevent interference and unwarranted operation by malicious or mischievous persons.

20 This invention not only provides a locking device which will positively prevent the unauthorized operation of the engine but also allows a vehicle provided with the engine in locked position to be pushed or pulled (by power other than its engine) out of danger in case of fire or accident or whenever a change of position is desirable in the garage or in the street.

25 This invention also provides an effective and safe locking device without in any way affecting the adjustment of the engine valves, the timing of the spark mechanism, clutches, brakes, gears, etc., but allows all adjustments to remain in any desired position while the engine is in locked position.

30 A further object of this invention is to provide a simple and effective locking de-

vice that can be attached to engines of well known types and of various sizes, and can be secured to various shafts of the engine, as, for example, to the crank-shaft, the timing shaft, the cam shaft, etc.

35 With these and other objects in view, the invention resides in the combination and arrangement of elements hereinafter described, illustrated in the accompanying drawings, and particularly pointed out in the appended claims.

40 In the drawings, Figure 1 is a longitudinal sectional view through the locking device in position on an engine shaft, showing the elements in the position assumed when the engine is operating. Fig. 2 is a side elevation 45 of the locking device, with a portion broken away and in section, showing the device in position on the crank shaft of an engine, and the elements in the position assumed when the engine is in an inoperative position. Fig. 3 is a detail elevation of one of the permutation tumbler locking rings, and, Fig. 4 is a side elevation of the inner sleeve 50 coacting with the permutation tumbler locking rings, the view being taken at right angles to the view shown in Fig. 1.

45 In the drawings, 1 designates a shaft of an internal combustion engine to which the locking device is attached and may be the crank-shaft, cam-shaft, timing shaft, etc., of the engine. The locking device has been found to be particularly practicable, however on the crank-shaft of the engine, and is shown as connected thereto in Fig. 2, of the drawings, this crank-shaft being designated 55 by the numeral 1^a.

50 The numeral 2 designates the master-gear of the engine, i. e., the gear carried by the crank-shaft which intermeshes with and actuates the gears which control the opening 55 and closing of the inlet and outlet valves, the timing of the spark mechanism, etc., and the primary feature of this invention, as illustrated in Fig. 2 is to provide a hand-operated locking connection between the crank-shaft and this master-gear so that when the engine is operating the master-gear will be rotated by the crank-shaft to accomplish its 60

usual function, but when it is desired to render the engine inoperative, the connection can be readily shifted to and locked in a position where the rotation of the crank-shaft will not affect the position of the master gear. In other words, the master gear would then be loose upon the crank-shaft, and while the crank-shaft may be rotated by other forces than the engine, as by a starting device or through the transmission mechanism when the vehicle is moved to a different place, this movement of the crank-shaft will not turn the master-gear to open and close the engine valves, etc., and accordingly, the engine will not operate.

The hand-operated locking device forming the connection between the crank-shaft and the master gear comprises a pulley 3 formed of two oppositely disposed pulley sections 4 each keyed to the crank-shaft and having oppositely disposed grooves 5 which together form a central annular groove for the reception of the shank 6 of the master-gear 2. The shank 6 fits loosely within the grooves 5 and is provided with a key-way or slot 8 adapted to align with a similar key-way or slot 7 in one of the pulley sections 4 for the reception of a slidable key or projection 9, carried at one end of the outer sleeve 12 mounted upon an intermediate sleeve 13 which in turn is slidably mounted on an inner sleeve 14 which is positively connected at one end to the collar 4^a of the pulley section 4, so that the rotation of the pulley section 4 keyed to the crank-shaft will serve to rotate the inner sleeve 14 connected thereto, and through connecting mechanism hereinafter described the inner sleeve 14 will rotate the intermediate and outer sleeves 13 and 12 respectively to revolve the master gear, the key or projection 9 carried by the outer sleeve 12 acting as a driver to turn this master gear. When, however, this key or projection 9 is slid out of the key-way or slot 8 in the master gear, it will be apparent that the master gear will not be rotated, but will remain in stationary position loose upon the pulley sections 4.

The inner sleeve 14 has one end secured to the collar 4^a of the pulley by set screws, screw-threads, or other suitable means, and at the other end is provided with an upstanding flange 15, while a portion of the periphery of this sleeve is annularly grooved or cut away, as shown at 16, to form a smaller annular portion with a shoulder 17 at the extremity thereof. Between the shoulder 17 and the flange 15 this sleeve carries one or more plates 18 provided with upstanding lugs or teeth 19, spaced at regular intervals along the plates. As shown in the drawings, two such toothed plates are provided, one 18^a spaced substantially 90° around the periphery of the sleeve from the

other, see Fig. 4, and one plate provided with 4 teeth or lugs and the other provided with 2 teeth or lugs. These toothed plates are secured to the sleeve 13 by set screws 20 and 20^a.

The intermediate sleeve 13 is shorter than 70 and loosely surrounds the inner sleeve 14 and is provided with slots 21 of greater length than the toothed plates 18 and 18^a and of sufficient width to allow these plates to project therethrough. These slots are of as much greater length than the toothed plates as it is desired to allow the sleeve 13 to slide to insert or withdraw the key into or out of operative position in the key-way of the master gear. At one extremity 80 the sleeve 13 has a thickened portion 23 the periphery of which is calibrated, as shown in Fig. 2. A portion of the slots 21 may be continued to form recesses in this thickened portion, as shown at 24 in Fig. 1, if desired. 85

The outer sleeve 12 is comparatively short in length and surrounds the intermediate sleeve 13 to which it is secured by set screws 25, or other suitable means. The key 9 is preferably formed integral with the sleeve 90 12 as is the inturned flange 26, which projects inwardly beyond the inner periphery of the sleeve 13. A washer 27 contacts with the flange 26 and is pressed against the flange by the coil spring 28 the other extremity of the spring abutting the shoulder 17 of the inner sleeve 14, and the spring 28 is preferably of sufficient strength to normally maintain the flange 26 and consequently the key 9 in advanced position to 100 drive the master gear. The sleeve 12 is provided at one extremity with the thickened portion 29, the periphery of which is calibrated, as shown in Fig. 2, and the end of this thickened portion 29 is spaced from the adjacent end of the thickened portion 23 of the sleeve 13 by a space sufficient for the accommodation of a plurality of permutation tumbler locking rings 30, four of such permutation tumbler locking rings being shown 110 herein. Each of the permutation tumbler locking rings is formed with an internal annular channel 31 and the walls of this channel are notched or cut away at intervals corresponding to the space between the toothed plates 18 and 18^a as shown at 32 and 32^a in Fig. 3, the notches being but slightly wider than the toothed plates so that only when the notches are properly aligned with the toothed plates can the permutation tumbler 120 locking rings be slid thereover. The channel 31 is of slightly greater width than each tooth or lug of the plates 18 and 18^a so that when the notched ring has been slid over a tooth or lug the ring may be turned to 125 throw the notch and tooth out of alignment, whereupon the ring cannot be slid in either direction along the sleeve until the notch

115

125

again is in proper alinement with the tooth. The periphery of each permutation tumbler locking ring is calibrated, as shown in Fig. 2, and it will be apparent that by a judicious placing of the notches in the permutation tumbler locking rings relatively to the numbers upon the periphery any desired combination of numbers can be arranged, which must always be brought into alinement upon the peripheries of the rings at one particular point to place the notches of all the rings in proper alinement to allow the sliding of the permutation tumbler locking rings and the sleeve 13 carrying these rings along the inner sleeve 14. When the notches and teeth are so alined the intermediate sleeve 13 may be moved along the inner sleeve 14 until it strikes the upstanding flange 15 thereon. Since the outer sleeve 12 is firmly secured to the sleeve 13 this sliding movement of the sleeve 13 will also slide the key 9 carried by the sleeve 12 to force it into or out of operative position within the key-way 8 of the master gear. From the foregoing, it will be apparent that with this locking device arranged on the crank-shaft of an engine, the engine may be operated as long as desired, the locking device in no way interfering with the ordinary operation of the engine. When however, it is desired to lock the engine against operation, the numbers upon the periphery of the permutation tumbler locking rings must be rotated to the position where all the notches of the several rings are in proper alinement with the toothed plates 18 and 18^a, and the sleeve 13 and 12 slid along the inner sleeve 14 to withdraw the key 9 from the master gear 2. The permutation tumbler locking rings are then rotated to move the notches out of alinement, and the engine is securely locked in an inoperative position, there being no longer any connecting means whereby the operation of the engine valves, the timing mechanism, etc., may be controlled. To restore the engine to operative position, the permutation tumbler locking rings are again rotated to bring the several notches and toothed plates into alinement, and the sleeves 12 and 13 moved to force the key 9 into the keyway 8 of the master gear. A further rotation of the permutation tumbler locking rings will then lock the engine in operative position. While the illustrated embodiment described herein has been found to be satisfactory, it is to be understood that this embodiment is intended to be merely illustrative and that various changes may be made therein within the scope of the appended claims.

A dial or other suitable mark may be secured to a part of the machine adjacent the peripheries of the locking rings so that the

location of the notches thereon may be readily referred to a fixed point.

Having described the invention, I claim—

1. In a locking device for engines, the combination with a rotatable shaft of the engine and a gear wheel loosely mounted thereon, of a connecting device secured to said shaft and provided with elements for imparting rotative motion from said shaft to said gear wheel when it is desired to operate the engine, said elements being also arranged to be moved into position wherein the gear wheel will not be rotated on the rotation of said shaft, and a series of manually operated permutation tumbler locking rings coöperating with the connecting device and arranged to lock the elements of the connecting device in either the operative or inoperative position.

2. In a locking device for engines, the combination with the crank-shaft of the engine and the master gear loosely mounted thereon of a connecting device having elements fixed to said shaft, other elements slideable into operative engagement with the master gear for imparting rotative motion from said shaft to said gear when in engagement therewith and also slideable into position wherein the master gear will not be rotated on the rotation of said shaft, and a series of permutation tumbler locking rings coöperating with the fixed and slideable elements of the connecting device for locking the slideable elements of the connecting device in or out of operative engagement with the master gear.

3. In a locking device for engines, the combination with a rotatable shaft of an engine and a gear wheel loosely mounted thereon, of a connecting device for imparting rotation from said shaft to said gear wheel, said connecting device comprising an inner sleeve secured to the shaft, outer sleeves slideable on but rotated by said inner sleeve, means carried by the outer sleeves adapted to be slid into and out of operative engagement with the gear, and manually operated permutation tumbler locking rings carried by the connecting device adapted to lock the outer sleeves in operative engagement with the gear wheel or in position whereby the gear wheel will not be rotated.

4. In a locking device for engines, the combination with a rotatable shaft of an engine and a gear wheel loosely mounted thereon, of a connecting device for imparting rotation from said shaft to said gear wheel, said connecting device comprising an inner sleeve secured to the shaft, outer sleeves slideable on but rotated by said inner sleeve, means carried by the outer sleeves adapted to be slid into and out of operative engagement with the gear wheel, and locking means

4.
carried by the connecting device adapted to lock the outer sleeves in operative engagement with the gear wheel or in position whereby the gear wheel will not be rotated, said locking means comprising a plurality of internally channeled permutation tumbler rings provided with spaced notches in their side walls and toothed plates carried by said inner sleeve, the teeth of said plates being

adapted to loosely fit within the channels of 10 said permutation tumbler locking rings.

In testimony whereof I affix my signature in presence of two witnesses.

LEWIS J. KNIEL.
